UNITED STATES PATENT OFFICE.

HENRY HARTMAN, OF LEWELLEN, NEBRASKA, ASSIGNOR OF ONE-THIRD TO ROBERT A. DAY, OF OSHKOSH, NEBRASKA.

HALTER.

1,184,643.

Specification of Letters Patent.

Patented May 23, 1916.

Application filed January 29, 1916. Serial No. 75,079.

To all whom it may concern:

Be it known that I, HENRY HARTMAN, a citizen of the United States, residing at Lewellen, in the county of Garden and State of Nebraska, have invented new and useful Improvements in Halters, of which the following is a specification.

This invention relates to improvements in halters, one object of the invention being to provide a halter in which the members are made of malleable steel, to secure strength and durability and are covered with leather or the like and thus caused to resemble straps; another object of the invention being to provide expansible cheek pieces for the halter so that the halter may be adjusted to fit a horse of any size; another object being to effect improvements in the construction of the link which connects the throat strap to the throat latch; and another object being to provide the throat latch with a snap hook for securing the halter on the horse's head.

The invention consists in the construction, combination, and arrangement of devices, hereinafter fully described and claimed.

In the accompanying drawings:—Figure 1 is a side elevation of a halter constructed and arranged in accordance with my invention. Fig. 2 is a front elevation of the same. Fig. 3 is a detail longitudinal sectional view on the plane indicated by the line *a—a* of Fig. 1. Figs. 4 and 5 are detail views.

The head stall 1, throat latch 2, cheek pieces 3, nose band 4, lip straps 5, and throat strap 6 are made of malleable steel as at 7 and are each provided with a cover 8 of leather or the like, the malleable steel construction rendering the halter extremely strong and durable and the covering serving to make the parts appear as straps and to protect the malleable steel parts from exposure to the weather. The ends of the malleable core of the head stall are double, engaged with rings 9, and riveted as at 10. The throat latch comprises a pair of members, the cores of which are similarly double, riveted and are engaged, one with one of the rings 9, and the other with a loop end 11 of a snap hook 12. The lower ends of the throat latch members 2 are similarly connected to opposite sides of a link 13, said link having a triangular upper portion 14 and a loop end 15, the latch members 2 be-

ing connected to the sides of the triangular portion of said link as shown.

The nose band 4 has the ends of its core member similarly connected to square links 16. Each cheek piece 3 comprises a member 17 connected to one of the rings 9 and a member 18 connected to one of the links 16. The members 18 are hollow and form sheaths to receive the members 17 and in which said members 17 are longitudinally adjustable so that the cheek pieces may be extended or contracted in length to vary the length of the halter so that the halter may be adapted to fit the head of a horse of any size. The members 17 and 18 of the cheek pieces are provided with adjusting openings 19 and 20 respectively and set screws 21 may be fitted in said openings to secure the members of the cheek pieces at any desired longitudinal adjustment.

The lip straps 5, are two in number, are connected at one end to the links 16, and have their lower ends connected to a triangular link 22 which is also engaged by a ring 23 which serves for the attachment of a rope, strap, or chain. The throat strap 6 connects the link 22 with the loop end 15 of the link 13.

By the provision of the snap hook and link ring for securing the throat latch, the use of a buckle in the throat latch is entirely dispensed with and the longitudinally adjustable cheek pieces also enable the buckles to be dispensed with.

My improved halter is exceedingly strong and durable, may be readily manufactured at slight cost, and is very serviceable, may be readily adjusted and may be easily put on or taken off from the head of a horse.

Having described the invention, what is claimed is:

A halter comprising a head strap, link rings connected to the ends thereof, cheek pieces having their upper ends connected to said link rings, links connected to the lower ends of the cheek pieces, a nose band having its ends connected to said links, a lip strap comprising two members having their upper ends connected to said links, a triangular link connected to the lower ends of said lip strap members, an attaching ring connected to said triangular ring, a throat latch comprising a pair of members one having its upper end connected to one of the

link rings and the other having its upper end connected to a snap hook for engagement with the other link ring, a link comprising a triangular portion, and a loop portion and having its triangular portion connected to the lower ends of said throat latch members, and a throat strap having its upper end connected to the loop portion of the

last named link and its lower end connected to said triangular link.

In testimony whereof I affix my signature in presence of two witnesses.

10

HENRY HARTMAN.
